ILLUMINATED ROAD MARKER

Theodore P. Dorn, Detroit, Mich.

Application December 6, 1937, Serial No. 178,409

1 Claim. (Cl. 88—79)

This invention relates to road markers of the light reflecting type so that visibility thereof will be efficient at night time and has for the primary object the provision of a durable and inexpensive device of this character which will remain firmly anchored in a roadway and will not readily become dislodged by a vehicle nor will it be hazardous to a vehicle when contacting the same.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a top plan view illustrating a road marker constructed in accordance with my invention.

Figure 2 is a sectional view taken on the line 2—2 of Figure 1.

Figure 3 is a sectional view taken on the line 3—3 of Figure 1.

Figure 4 is a sectional view taken on the line 4—4 of Figure 2.

Figure 5 is a sectional view taken on the line 5—5 of Figure 2.

Referring in detail to the drawing, the numeral 1 indicates a top plate having a convex curvature and provided with a depending peripheral flange 2 adapted to rest upon a base 3. The outer face of the top plate is preferably knurled as shown in the drawing in Figure 1, and is provided with a series of openings for the reception of cups 4. The walls of the openings are shouldered engaged by flanges on the cups. The cups support light reflecting elements 5 exposed to view so that when the light rays from a vehicle shine thereon the light rays will be reflected back to the driver of the vehicle. The cups have formed thereon screw threaded shanks 6 that extend through washers 7. The washers engage the inner face of the top wall. Nuts 8 are threaded onto the shanks 6 against the washers. The washers cooperate with the flanges of the cups in firmly anchoring the cups in the openings of the top plate.

The base 3 is of annular formation and is

provided with an integral cross member 9 having formed thereon an anchoring post 10 adapted to be positioned in a recess or socket formed in a roadway. The anchoring post 10 gradually tapers from its unattached end to its attached end. The cross member 9 has integral therewith a rib 11, the upper edge of which is shaped to conform to the contour of the top plate and engages therewith. The upper edge of the rib may be notched to receive washers of 10 certain of the cups and also is provided with notches 12 in the lower edges thereof defining openings between the rib and the cross member 9. The ends of the rib are provided with notches 13 in which are adapted to move lugs 14 integral 15 with the flange 2 of the top plate for the purpose of anchoring the top plate on the base. The top plate may have one or more pouring openings 15, the purpose of which is to permit liquefied lead to be poured into the device filling the 20 space between the base and the top plate and the space between the walls of the post and the socket in the roadway which receives the post, thereby firmly anchoring the device in the roadway and the parts of the device together. The 25 lead when hardened prevents accidental displacement of the device from the roadway and separation of the parts from each other. As the lead completely fills the space between the top plate and base and passes through the 30 notches in the rib, said top plate cannot become accidentally disconnected from the base.

What is claimed is:

A reflector mount for a road marker, comprising a base plate, a top plate releasably engageable with the base plate, said top plate having openings, cup-like members accommodated within said openings, fasteners securing the cup-shaped members in said openings and concealed between the top and base plates, a rib carried 35 by the base plate and shaped to conform to and contacting with said top plate, said rib having notches, lugs formed on the flange to engage certain of said notches, and a filler between the 40 said plates and carried into the notches past 45 said ribs for anchoring the top and base plates together.

THEODORE P. DORN.
